BOBBIN CLUTCH

Application filed August 26, 1930. Serial No. 477,812.

This invention pertains to that type of spindles commonly employed in spinning and other textile operations, and relates particularly to an improved bobbin clutch having expandable clutching members which maintain the bobbin in position during the spinning or other operation.

The objects of this invention are to provide a bobbin clutch which is simple and economical to manufacture and assemble, which is efficient and durable in use, and which is generally superior to bobbin clutches now in use. Further objects will be apparent as attributes of the novel construction hereinafter shown and described.

For the purposes of illustration, one concrete embodiment is shown in the accompanying drawings, in which:

Fig. 1 is a vertical cross-section of a bobbin clutch embodying a preferred construction showing the contact segments in an expanded relation;

Fig. 2 is a view similar to Fig. 1 showing the contact segments in a contracted relation;

Fig. 3 is a transverse cross-section taken on the line 3—3 of Fig. 1, with the cap removed; and

Fig. 4 is a plan view of the spring element. The particular embodiment of the invention chosen for the purpose of illustration comprises an ordinary blade 1 and a whirl 2 fixedly mounted on the blade by a pressed fit, the whirl 2 having a hub (or shoulder) 3 and

an annular flange 4 projecting laterally from its lower periphery. An annular neck 5 provided with a ring 6 is disposed on the upper surface 3^a of the hub 3. The upper surface of the hub 3 may be in a horizontal plane

but is preferably acclivous from the upper periphery of the hub 3 to the lower periphery of neck 5, the portion of the hub between the planes of the two peripheries being a frustoconical section. The upper surface 3^a of the

hub hereinafter will be referred to as the shoulder surface.

Mounted on the blade 1 in opposition to the hub 3 is a case 7 having four radial slots extending longitudinally from one end throughout the major portion of the case,

leaving therebetween symmetrically disposed, circumferentially spaced fingers 8 which extend downwardly with their lower ends circumjacent to the neck 5 and the ring 6. Disposed in the aforesaid slots are the contact segments 9 of the clutching members 10 having their upper ends lipped to engage inside the case and their lower interior walls engaging the fulcrum ring 6, as shown in Fig. 1. The declivous quadrant-shaped wings 11 carry skirt portions 12, each provided with a lateral groove 13.

A coiled spring 14 with ends connected is disposed in the lateral grooves 13 and encircles the skirt portions 12 of the clutching members. The spring being normally under tension is secured in the position shown in Figs. 1 and 2, and also holds the clutching members 10 in a normally operative relation. It is apparent that each of the clutching members acts as a lever fulcrumed on the ring 6. The cap 15 is provided with a circular opening 16 in the center of its horizontal surface 17, the opening being slightly greater in diameter than the external diameter of the bobbin clutch measured from one expanded contact segment to the diametrically opposite segment in the plane of the opening. The cap is fitted on the flange 4 of the whirl, as shown in Figs. 1 and 2, and thus serves not only as a housing but also as a bobbin seat.

In assembling the parts the whirl 2 is preferably applied to the blade 1, first; the ring 6 is then pressed on the neck 5, and the case 7 is then pressed on the blade 1 so that the lower ends of its fingers 8 abut the shoulder surface 3^a or remain suspended just above its surface. The clutching members are then applied with their contact segments 9 disposed in the slots between the fingers 8 having their lipped ends engaging the case, and having their wing members 11 disposed in superjacent relation to the shoulder surface 3^a. The spring 14 is dropped on over the skirt portions 12, and the cap 15 is then applied in similar manner and pressed on the flange 4.

Due to the slight tension normally exerted by the spring, the skirt portions 12 will be

contracted in relation to the cylindrical wall of the hub 3 and the lever action about the fulcrum ring 6 will cause the contact segment to assume an expanded relation limited by 5 their lipped ends abutting the interior of the case 7. When a bobbin is applied over the blade 1 and thence over the case 7 until it rests on the horizontal surface 17 of the cap 15, the contact segments 9 will be pressed inwardly causing the skirt portions 12 to expand and increase the tension exerted by the 10 spring 14, whereupon the contact segments, due to the reacting resistance thus produced, will press against the bore of the bobbin and 15 hold it in operative position.

In the preferred construction above described, the contact segments fit snugly in the slots between the fingers 8, and the cap 15 fits over the case and clutching member with just 20 enough clearance between the latter members and the edge of the circular opening 16 to prevent any interference with the free movement of the clutching members 10. This construction prevents dirt, dust and yarn 25 from entering to any substantial extent the interior of the case and thus affords a protection which will insure an unimpaired operation of the clutching members.

It should be noted the arcuate skirt portions 12 carrying the spring 14 are positioned around the hub to define a cylindrical skirt, and when a bobbin is applied over the case 7, the contact segments are pressed inwardly and the skirt portions 12 are expanded symmetrically to define a greater circumference and thus cause a corresponding symmetrical expansion of the spring. The spring reacts 35 symmetrically and evenly and causes each of the contact segments to press firmly against the bore of the bobbin and thus hold it securely in position.

As the expansion of the contact segments is limited only by their lipped ends engaging the case, and as the spring exerts a reactive 45 tension at all times and in all positions of the contact segments, the latter will yieldingly engage and firmly hold in position bobbins having bores varying greatly in diameter.

It should be understood that the present 50 disclosure is for the purpose of illustration only and that this invention includes all modifications and equivalents which fall within the scope of the appended claims.

I claim:

55 1. Apparatus of the character described comprising a blade, elongate members distributed around the blade with their long dimensions extending longitudinally of the blade for yieldingly holding a bobbin on the 60 blade, means mounted on the blade to provide a fulcrum for each member intermediate its ends so that when one end moves toward the blade the other end moves away from the blade to hold the bobbin, and a spring 65 urging the first end toward the blade, each

member being bent outwardly from the blade intermediate said fulcrum and said spring.

2. Apparatus of the character described comprising a blade, a whirl mounted on the blade and having an annular shoulder and 70 a neck having an annular fulcrum, a case mounted on the blade and having downwardly extending, spaced fingers, bobbin clutching members having their contact segments disposed in the spaces between said fingers and their lower ends in circumjacent relation to said shoulder and bearing on said fulcrum intermediate said ends, and resilient means 75 retaining the contact segments in an expanded position.

3. Apparatus of the character described comprising a blade, a whirl mounted on the blade, the whirl having a hub provided with a neck, a ring fitting about said neck, a case mounted on the blade and having spaced fingers with ends disposed in circumjacent relation to the neck, bobbin clutching members having their contact segments disposed in the spaces between said fingers, the central portion of the inner walls being pivoted about said ring and their lower ends disposed in circumjacent relation to the hub, and resilient means 80 encircling the lower ends of said clutching members and acting thereon to produce a normally relative radial contraction whereby the contact segments are expanded. 85

4. Apparatus of the character described comprising a blade, a whirl mounted on the blade, the whirl having a hub with an annular flange projecting from its lower end and a neck disposed on its upper surface fitting around the blade, a case mounted on the blade and having spaced fingers extending downwardly with ends adjacent to the hub, a fulcrum ring, bobbin clutching members fulcrumed about said ring with their contact segments disposed in the spaces between said fingers and having their lower portions disposed in circumjacent relation to the hub, a coiled spring encircling the lower 100 portions of the clutching members normally retaining them in a contracted relation, and a cap fitting on the annular flange and enveloping the lower ends of the clutching members. 105

5. Apparatus of the character described comprising a blade, a whirl mounted on the blade, the whirl having a hub with an annular flange projecting from its lower end and a neck disposed on its upper surface fitting around the blade, a fulcrum ring on 110 said neck, a case having a plurality of similar, symmetrically disposed, circumferentially spaced fingers extending downwardly with ends circumjacent to the neck, a plurality of 115 bobbin clutching members fulcrumed about said ring and having their contact segments disposed in the spaces between the fingers and having their lower portions symmetrically disposed in circumjacent relation to the 120 125 130

hub, said lower portions each being provided with a groove running laterally, a coil spring disposed in said grooves and encircling the lower portions of said clutching members, said spring normally retaining the lower portions of the contact members in a relatively contracted relation, and a cap fitting on the annular flange and enveloping the lower ends of the clutching members.

6. Apparatus of the character described comprising a whirl having a hub and an annular neck concentric therewith, a ring fitting around the neck, a case having downwardly extending spaced fingers, bobbin clutching members fulcrumed about said ring and having their contact segment disposed in the spaces between said fingers, and having their lower ends extending downwardly to the hub, and a spring engaging the lower end of said clutching member normally retaining the contact segments in an assembled and expanded relation relative to said case.

7. Apparatus of the character described comprising a blade, a whirl mounted on the blade, the whirl having a hub provided with a neck fitting around the blade and an annular flange projecting from the lower end of said hub, a ring fitting around the neck, a case mounted on the blade and having spaced fingers extending downwardly, bobbin clutching members having contact segments provided with lipped upper ends, the lower ends of the clutching members having cylindrical skirt portions each provided with a groove running laterally, said contact segments being disposed in the spaces between said fingers with their lipped ends interiorly of the case, the interior lower portions of said contact segments being fulcrumed about the ring, and the skirt portions being disposed in circumjacent relation to the hub, a coiled tension spring disposed in the grooves of said skirt portions and encircling the same, said spring normally retaining the contact segments in an expanded relation relative to the case, and a cap fitting on the annular flange.

8. Apparatus of the character described, comprising a blade, a whirl mounted on the blade and having an upwardly extending annular projection in concentric juxtaposition to the blade, a case mounted on the blade and having downwardly extending spaced fingers, bobbin clutching members having their contact segments disposed in the spaces between said fingers, resilient means disposed concentrically about the projection and tending to press the lower ends of said members inwardly, the latter rocking about fulcrum axes provided between said projection and members and below the upper end of the said projection, whereby the contact segments are urged outwardly in radial directions.

9. Apparatus of the character described,

comprising a blade, a whirl mounted on the blade and having a neck in juxtaposed concentric relation to the blade, a case mounted on the blade and having downwardly extending, spaced fingers, bobbin clutching members having their contact segments disposed in the spaces between said fingers and rocking on fulcrum axes between the members and neck and below the top of the neck, resilient means pressing the lower ends of said fingers inwardly, and a cap engaging the whirl and enveloping the lower parts of said members.

Signed by me at Boston, Massachusetts, this 20th day of August, 1930.

GEORGE H. MAGRATH.
